US00D736106S

(12) **United States Design Patent**
Bowman et al.

(10) **Patent No.:** **US D736,106 S**
(45) **Date of Patent:** ** *Aug. 11, 2015

(54) **ELECTRONIC DEVICE**

(71) Applicant: **Garmin Switzerland GmbH**,
Schaffhausen (CH)

(72) Inventors: **Marcos J. Bowman**, Overland Park, KS
(US); **Mark B. Emge**, Olathe, KS (US);
Jonathan K. Ferlas, Prairie Village, KS
(US); **Yi-Chung Lan**, New Taipei (TW)

(73) Assignee: **Garmin Switzerland GmbH** (CH)

(*) Notice: This patent is subject to a terminal disclaimer.

(**) Term: **14 Years**

(21) Appl. No.: **29/471,957**

(22) Filed: **Nov. 6, 2013**

(51) LOC (10) Cl. **10-04**

(57) **CLAIM**

The ornamental design for an electronic device, as shown and described.

DESCRIPTION

FIG. 1 is a front perspective view of an electronic device according to embodiments of the present invention;

FIG. 2 is a rear perspective view of the electronic device;

FIG. 3 is a top view of the electronic device;

FIG. 4 is a front view of the electronic device;

FIG. 5 is a rear view of the electronic device;

FIG. 6 is a bottom view of the electronic device;

FIG. 7 is a left side view of the electronic device; and,

FIG. 8 is a right side view of the electronic device.

Portions of FIGS. 1 through 8 are shown in dashed lines for illustrative purposes only and form no part of the claimed design.

1 Claim, 5 Drawing Sheets
